CLAIM

The ornamental design for a Christmas advent calendar ferris wheel with drawers, as shown and described.

DESCRIPTION

FIG. 1 is a perspective view of the Christmas advent calendar ferris wheel with drawers showing my new design; FIG. 2 is another perspective view thereof.

FIG. 3 is a front view thereof;

FIG. 4 is back view thereof;

FIG. 5 is a left side view thereof;

FIG. 6 is a right side view thereof;

FIG. 7 is a top view thereof; and,

FIG. 8 is a bottom view thereof.

The broken lines in the drawing depict environmental subject matter only and form no part of the claimed design.
